UNITED STATES PATENT OFFICE.

BOHUMIL JIRAUCH, OF ST. LOUIS, MISSOURI.

WATCHCASE.

1,177,111.

Specification of Letters Patent. Patented Mar. 28, 1916.

Application filed October 16, 1915. Serial No. 56,322.

To all whom it may concern:

Be it known that I, BOHUMIL JIRAUCH, a citizen of the United States, residing at St. Louis city, State of Missouri, have invented a new and useful Watchcase, of which the following is a specification.

In watch cases which may be locked and which are water proof and dust proof.

I attain these objects by the mechanism illustrated in the accompanying drawing, in which—

Figure 1 is a sectional view or cross section of the two halves of the watch case; Fig. 2 is a cross section 2—3 of the pendant 15 and entire watch case; Fig. 3 is a cross section of the crown showing the sleeve shell, pendant halves; Fig. 4 is a view of the shell which fits over the pendant; Fig. 5 is a cross section of the lock nut which fits over the shell and screws onto the pendant.

The case halves C and D, together with the drums I and J contain the watch movements and fit together at the bearing surfaces F, and are clasped by screwing the 25 male and female threads G and H.

When the halves C and D are fitted to-

gether the pendant halves K and L form a threaded cylinder pendant around which the bow ring shell M fits and onto which the lock nut N is screwed, which holds the shell 30 down and clasps the two halves of the pendant. Through an opening P in the lock nut the usual catch stem fits, the crown Q fits onto the lock nut with bearing surfaces at R S. 35

I claim:

The combination of two watch case halves, fastened together by male and female threaded drums, which are part of the case halves, the watch case halves having a split 40 threaded pendant, a bow ring shell fitted around the pendant holding the watch case halves in place, an internally threaded lock nut screwed about the pendant and above the bow ring shell, and a crown and stem 45 fitted around and through a lock nut, all arranged and operated substantially as described.

BOHUMIL JIRAUCH.
